HEINRICH WALDES, OF WRSCHOWITZ, NEAR PRAGUE, AUSTRIA-HUNGARY.

FEEDING MECHANISM FOR BUTTON-SEWING MACHINES.

1,110,843.

Specification of Letters Patent. Patented Sept. 15, 1914.

Application filed July 9, 1913. Serial No. 778,051.

To all whom it may concern:

Be it known that I, HEINRICH WALDES, a subject of the Emperor of Austria-Hungary, and residing at Wrschowitz, near Prague, 5 Bohemia, Austrian Empire, have invented a certain new and useful Improvement in Feeding Mechanisms for Button-Sewing Machines, of which the following is a full, clear, and exact description.

10 The parts of spring pressed buttons are now not usually sewn onto material forming the closure, but are attached to a strip of material or tape, which is then sewn on to the article to be provided with the closure.

15 The button parts are attached by means of sewing machines of the known kind, the needle of which passes through the holes of the button piece and sews the same on to the strip.

20 Now the present invention consists of means for feeding the parts of the spring pressed button at regular intervals to the sewing machine, under the needle and means for transporting the strip or tape to which the button parts are to be sewn, a certain predetermined distance between the feed of each button part.

25 In the accompanying drawings which illustrate one form of embodying the present invention, Figure 1 is a side elevation of the device, Fig. 2 a plan, Fig. 3 a rear elevation, Fig. 4 a side elevation of the means for clamping and transporting the strip, Fig. 5 a side elevation of the device for feeding the button part, Fig. 6 a front elevation showing a form of coupling for intermittently operating the device, Fig. 7 a longitudinal section through the coupling and Figs. 8 and 9 cross sections showing the coupling in two different positions.

30 The sewing machine itself is not illustrated, the axis of the same being indicated in Fig. 2 by means of the line 1.

35 A shaft 3 (Fig. 1) is mounted on the work table of the sewing machine and driven from the main shaft 2 of the latter by means of chain gearing. By means of this shaft the mechanism for feeding the buttons and transporting the strip is operated. The shaft 3 is intermittently rotated by means of a coupling located between the boss of the chain wheel 4 and the shaft 3 and illustrated in Figs. 6, 7, 8 40 and 9. The coupling consists of a bolt 5 of segmental cross section and adapted to

rotate in a groove of the shaft 3. This bolt 5 lies partly in the groove but is capable, when turned axially to extend with one edge into one of a series of recesses 10 formed 45 in the boss of the chain wheel 4 and when in this position to couple the latter to the shaft 3. A collar 8 is provided on the shaft 3 and the bolt 5 has a radial arm 6 adapted to turn through an arc limited by a recess 7 50 in said collar, in which the said arm lies. A contractile spiral spring 9 is connected at one end to the pin 8' on the collar 8 fixed to the shaft 3 and at the other end to the radial arm 6 and operates to normally hold said 55 arm against one side of the recess 7 in the position in which it is shown in Fig. 9. In this position the segmental bolt 5 projects above the periphery of the shaft 3 and engages the hub of the chain wheel 4 and 60 locks it to the shaft. A sliding stud 11 is mounted in the machine frame as best shown in Fig. 1. A bell crank lever 12 disposed on a pivot stud 12' engages a stud 11' on said sliding stud 11 for thrusting the latter into 65 the path of the arm 6 and retracting it therefrom. A horizontal lever 13 pivoted on a bracket 13' is connected at its outer ends with the other arm of the bell crank lever 12. A rod 13' connects the inner end 70 of the lever 13 with the sewing machine mechanism not shown. When the sliding stud 11 is thrust into the path of the arm 6 and the turning of the shaft 3 brings said 75 arm into contact with said stud, the arm is held stationary until the parts assume the 80 position shown in Fig. 8, whereby the segmental bolt 5 is turned so that it is flush with the periphery of the shaft 3 or entirely within the groove thereof, and the chain 85 wheel 4 is then free to turn loosely on the 90 shaft 4.

95 Cam disks are mounted on the shaft 3 one of which 14 operates to reciprocate a bar 16 by means of a double arm lever 15. The bar 100 16 carries stops 17, 18 between which the bifurcated arm 19 of a pivotally mounted bell crank lever engages. The other arm 20 of the latter engages by a fork and pin connection with a slide 21 moving in a guideway 22 of a plate. This guideway 22 serves for the reception one by one of the buttons 23 and opens up into a guideway 24 lying at right angles to the same and formed in the plate 25, having mounted therein a movable slide 26. The latter is provided with an upwardly extending pin 27 adapted to 105 110

engage the bifurcated end of an arm 29 pivotally supported on the bar 16 and depressed by means of a spring 28. This arm 29 moves with the bar 16 and also passes along a cam surface 30 at the side of one of the grooves forming the guideway 24, so that, on the rearward movement of the bar 16, it will be raised by the said cam surface and release the pin 27 of the slide 26, allowing the latter to remain stationary. In this stationary position of the slide 26, the ends of the two guideways 22 and 24 open up one into the other, so that the button 23 may be pushed from the groove 22 into the groove 24 by means of the arm 20 of the bell crank lever, in order to be passed under the needle of the machine by the slide 26 which has in the meantime been moved forward again. As the bar 16 moves forward the arm 29 slides down the cam surface 30 and again engages the pin 27 of the slide 26. The slide 26 is held down in its guideway by means of a spring pressed arm 31.

The second cam disk 32 of the shaft 3 operates a horizontally guided rod 34 by means of a slotted rocking lever 33 and a slide rod 35. The rod 34 is connected by means of a bracket arm 36 (Fig. 4) to a slide 37 guided in a guideway 38 of a plate 39 attached to the base plate of the device. The slide 37 passes through a slot of a second slide 40 also guided in the plate 39, and adapted to support the strip 41 to which the buttons are to be sewn.

The slide 37 is provided with an upwardly extending nose 42 (Fig. 3) which is located between a bearing 43 on the slide 40 and a downwardly extending finger 44 mounted on one end of a double lever pivotally supported in the said bearing and the opposite end of which carries a clamping piece 45 adapted to press on the slide 40 and to clamp the strip 41 thereto, so that it will be moved with the slide.

Thus if the rod 34 is moved backwardly the nose 42 of slide 37 will contact with the finger 44 and clamp the strip 41 to the slide 40. On the further movement of the rod 34 the strip will be moved a distance corresponding to the distance apart of the buttons. As the rod 34 performs its return movement the nose 42 will release the finger 44, the presser or clamping piece is raised from the strip, which latter has in the meantime been retained by the presser foot of the sewing machine and the nose 42 then engages the bearing 43 and on further movement returns the slide to its initial position.

The two mechanisms above described co-operate in the following manner:—Fig. 2 shows the parts in their respective positions just as the coupling of the shaft 3 is to come into engagement and a button has been sewn on to the band. The coupling of the shaft 3 to the chain wheel 4 is effected

by the arm 6 under the action of the spring 9 after the withdrawal of the sliding stud 11. At the same time the needle bar of the sewing machine was raised and the strip released. The shaft 3 is consequently rotated, thus turning the cam disks 14 and 32. The bar 16 and rod 34 are each reciprocated once during the engagement of the members 4 and 5. The reciprocation of the parts 16 and 34 causes a fresh button to be fed to the machine and simultaneously effects the transport of the strip. In order to be able to adjust the transport of the strip, the rod 34 is connected to the end of the double lever 33 by means of a screw and slot connection 46 (Fig. 3) so that the length of transport may be adjusted.

I claim as my invention:

1. Device for feeding parts of spring pressed buttons singly to the needle of a sewing machine and for intermittently transporting the band of fabric to which the said parts are to be attached comprising a feed guideway to receive the said button part, a slide to move the same under the needle of the sewing machine, a second slide over which the band passes, a clamping device to periodically clamp said band to the slide, a shaft having cam disks thereon to operate said slides, a driving gear loosely mounted on said shaft and means for locking said gear to its shaft.

2. Device for feeding parts of spring pressed buttons singly to the needle of a sewing machine and for intermittently transporting the band of fabric to which the said parts are to be attached comprising a feed guideway to receive the said button part, a slide to move the same under the needle of the sewing machine, a second slide over which the band passes, a clamping device to periodically clamp said band to the slide, a shaft having cam disks thereon and means for intermittently rotating the same a single rotation, sliding bars reciprocated by said cam disks, and connections between said bars and slides to operate the slides to transport the button part to sewing position and to transport the band and means for releasing the band clamp at the end of each feeding operation.

3. Device for feeding parts of spring pressed buttons singly to the needle of a sewing machine and for intermittently transporting the band of fabric to which the said parts are to be attached comprising a feed guideway to receive the said button part, a slide to move the same under the needle of the sewing machine, a second slide over which the band passes, a clamping device to periodically clamp said band to the slide, a shaft having cam disks thereon and means for intermittently rotating the same a single rotation, sliding bars reciprocated by said cam disks, and connections between said bars

and slides to operate the slides to transport the button part to the needle and to transport the band, means for releasing the band clamp at the end of each feeding operation and an adjustable connection between the band transporting slide and its operating bar.

4. In a button sewing machine, the combination of a button feed mechanism, a button strip feed mechanism, a cam shaft provided with a longitudinal groove, cam disks on said cam shaft for actuating said mechanisms respectively, and a clutch device on said cam shaft comprising a pulley loose thereon and provided with a recess in its hub, an oscillatory segmental coupling bolt disposed in the groove of said cam shaft and adapted to turn axially to engage or release said pulley and provided with a radial arm having a limited arc-movement, a spring engaging said arm and normally holding said segmental rod in engagement with said hub, a movable stud and means for thrusting and retracting said movable stud into and out of the path of said radial arm.

5. A button feed mechanism for a sewing machine comprising a main guideway hav-

ing a button rest at one end adapted to hold a button in position to be stitched, a slide in said guideway movable parallel with the feed of the material and provided with an upward stud, a stationary lifting cam adjacent to said slide, a guideway disposed laterally to the main guideway, an auxiliary slide therein adapted to push a button therefrom into the main guideway, an endwise reciprocating slide bar disposed parallel to the feed of the material and provided with stops, means for intermittently reciprocating said bar, a bell crank lever whereof one end engages said auxiliary slide and the other end is engaged by said slide bar between said stops, and a spring depressed arm pivoted on said slide bar and adapted to engage the upward stud of said main slide during the movement of said bar and to be released therefrom by said cam during said movement.

In testimony whereof I affix my signature in the presence of two witnesses.
